UNITED STATES PATENT OFFICE.

DEWEY O. PEARCE, OF BOISE, IDAHO.

INFLATABLE BALL.

Application filed April 5, 1923. Serial No. 630,010.

To all whom it may concern.:

Be it known that I, DEWEY O. PEARCE, a citizen of the United States, residing at Boise, in the county of Ada and State of Idaho, have invented certain new and useful Improvements in Inflatable Balls, of which the following is a specification.

This invention relates to an improvement in inflatable balls, and particularly to a structure adapted to be embodied in basket-balls, foot-balls, striking-bags, and other like inflated balls or bags.

An object of my invention is to provide an outer casing and an inflatable inner portion which are so constructed and associated that the ball is evenly balanced to carry true in its flight when in motion, and in providing a closure portion for the outer casing and an inflating portion for the inner member which are entirely within the outer lines of the ball or bag, and thus leave the outer surface free of projections.

A further object resides in so constructing the closure portions and the inflating portion that these will be entirely covered by the leather or other material of the outer casing and that the parts are thus protected to prevent danger of breaking the finger nails, scuffing the knuckles, or injuring the skin or flesh of the face or body of the party using the ball or bag.

Another object lies in providing a closure and inflating portions which are of such construction that the inflatable portion can be filled with air without the necessity of loosening the fastenings of the outer casing, and that the outer and inner portions are connected together and are so assembled that the bag or ball will have a true form at all times when inflated.

With the above and other objects in view, which will be apparent to those skilled in the art, my invention includes certain novel features of construction and combination of parts which will now be set forth.

In the drawings:

Figure 1 is a view in elevation looking at the closure side of a foot-ball embodying my invention.

Fig. 2 is a similar view looking at the opposite side.

Fig. 3 is a transverse sectional view through the casing and the inflatable portion.

Fig. 4 is a detail sectional view to better show the connection of the inflating valve. 55

Fig. 5 is a view in perspective showing the closure hook and eye. 60

In the present instance, I have shown my invention embodied in conjunction with a regulation form of foot-ball, but it will be appreciated that the invention is applicable to spherical balls, and can also be applied in conjunction with striking bags of the standard pear form or of any other shape. 65

As illustrated in Fig. 1, the casing 1 has the usual slit or opening 2 therein through which access is had to the interior for placement and removal of the rubber bladder or other inflatable portion. This slit or opening 2 has the reinforcing members or gaskets 3 and 4 secured along the edges thereof, and the usual flap 5 is provided to close the opening on the inner side. A plurality of hooks 6 are secured on one side of the slit 7, and an equal number of eye members 7 are secured in registering relation on the opposite side of the slit. The hooks 6 and eye members 7 are associated with the gasket 3 and 4 in such a manner that a substantially smooth inner surface is presented against the closing flap 5, and the material of the case 1 overhangs as at 8, to entirely cover the interlocked ends of the hooks and eye members. The hooks 6 and eye members 7 are secured in place by stitching, riveting or other suitable fastenings, and it is preferable that the same fastenings be employed to secure the gaskets 3 and 4 in conjunction with the outer casing 1, as in this way a substantially integral structure is obtained. 75

A rubber or other inflatable portion 9 is shaped to correspond with the casing 1, and is provided with a metallic inflating valve 10 having an extending stem 11. The casing 1 is provided with a valve stem opening 12 at a point diametrically opposite the slit or opening 2, and the reinforcing washers or gaskets 13 and 14 are secured on the inner side of the case around this opening. These washers or gaskets are preferably of leather or other material which will flex with the casing, and a polygonal nut 15 is introduced in washer 13 to receive the threaded end of valve stem 11. This valve stem is preferably locked in place within the opening of the rubber bladder or inflat- 100 105

able portion 9 by means of a nut 16, and a cap 17 is provided to close the end of the valve stem.

In the use of my improved structure the 5 lacing hooks 6 are disengaged from the eye members 7 and the slit 2 may then be opened to give access to the interior of the casing 1. The bladder 9 is then inserted into the casing and the valve stem 11 is turned into 10 nut 15 to present the open end thereof within opening 12 of the casing 1. The hooks 6 are then caught within the eyes 7 and the portion 9 is inflated through the valve stem 11, this stem being properly threaded for 15 attachment of a pump or other air supplying appliance, and as the closing flap 5 is forced outwardly and casing 1 is expanded, the hooks will be firmly held within the eyes. With this construction and arrangement of 20 the parts, it is not necessary to disassemble the two portions of the ball, nor loosen the hooks when the ball is in use, as air can be supplied through the valve stem 11 and the ball can be kept inflated to the proper 25 pressure at all times.

Where my improvements are embodied in a striking bag, it may be found desirable to locate the slit and the valve structures at one end, but in this arrangement care should 30 be taken to locate the valve diametrically opposite the slit to preserve the balance of the bag. Further, it will be appreciated that other changes can be made in the form and arrangement of the parts to adapt my 35 invention to the particular construction of

the ball or bag in which it is being embodied, without departing from the spirit or scope of my invention.

I claim:

1. An inflatable ball comprising a casing having a slit therein, a plurality of hooks carried by said casing on one side of the slit, a plurality of eye members mounted on the casing on the opposite side of the slit, gasket portions carried by the casing on the 45 inner side adjacent the hooks and eye members to present a smooth inner surface, a closing flap carried on the inner side of the casing to close over the slit, and an inflatable portion within the casing. 50

2. An inflatable ball comprising a casing having a slit therein, a plurality of hooks carried by said casing on one side of the slit, a plurality of eye members mounted on the casing on the opposite side of the slit, 55 gasket portions carried by the casing on the inner side adjacent the hooks and eye members to present a smooth inner surface, a closing flap carried on the inner side of the casing to close over the slit, an inflatable 60 portion fitted within the casing through said slit, said casing having an inflating opening at a point diametrically opposite the slit, an inflating valve stem carried by the inflatable portion, and means associated with the 65 casing to hold said valve stem adjacent the inflating opening of the casing.

In testimony whereof I affix my signature.

DEWEY O. PEARCE.
